COMBINATION LOCK

Olof Hage, Goteborg, Sweden

Application February 10, 1943, Serial No. 475,337

In Sweden April 7, 1942

5 Claims. (Cl. 70—305)

The present invention refers to combination locks for safes for instance of the type shown in the U. S. Patent No. 2,104,516. The object of the invention is to improve the efficiency of combination locks and reduce the possibility of unauthorized opening thereof.

In locks of said type the lock spindle extends through the door and the tumblers of the lock are turned by means of an arm or the like attached to the spindle. When adjusting the tumblers for unlocking the lock, notches in the tumblers are brought into position underneath a cross bar which cross bar being swung into said notches permits a free displacement upwardly of the bolt.

In practical use such locks have been found to lack the desired high degree of precision and protection.

The present invention removes said disadvantages and makes it impossible to unlock the lock with an incorrect letter combination. The invention is principally characterized by the provision in a lock of the type above referred to of a straight guide for the cross bar and of an effective key device for connecting the adjusting arm and the lock spindle.

In the accompanying drawing one embodiment of the invention is illustrated by way of example. Fig. 1 is a view of the lock viewed from the inner side of the door, the cover plate being removed and the members being set for unlocking. Fig. 2 is a section on line II—II in Fig. 1. Fig. 3 shows the device viewed from above with a corresponding cover removed and a portion of the bolt in section. Fig. 4 shows some members in the position when the lock is unlocked. Fig. 5 is a detail plan view of the key connecting the spindle and actuating arm and Fig. 6 is a section on line VI—VI in Fig. 4.

For convenience, parts corresponding with those disclosed in the patent mentioned above have been given the same designations as in the patent.

The lock comprises a lock house with lock members. The lock spindle 48 is rotatably mounted in the bottom plate 2 of the lock house and the lock bolt 55 extends through a side wall 4 of the house. To the spindle is attached an angular arm 42 which by means of intermediate toothed rings acts on tumblers 19 which are rotatably mounted on a bolt 18 and provided with notches 21. The notches 21 coat with a cross bar 18 normally blocking the lock bolt but which permits the bolt 55 to be pushed into the house, when the notches are placed in register underneath the cross bar.

The cross bar 18 extends from a plate 17 which to the right (Fig. 4) is provided with an oblique edge 83 and with an abutment 79. The plate 17 has two depending guiding legs 80, 81. On a plate 15 resting against the bottom plate 2 is a guide 16 which is T-shaped in cross section and is attached by means of the bolt 18, this guide and the plate 15 forming together guiding channels for the legs 80, 81, so that the cross bar 18 must move along a straight line in the radial direction of the bolt 18, which also is the centre for the tumblers 19. In order to withstand side pressure applied to the plate 17 arising from the inward movement of the lock bolt 55, a pin 17 is attached to the plate 15.

The lock bolt 55 is displaceable in an aperture in the side wall 4 and extends to the left in Fig. 1 into the lock house, terminating in a bolt shank 56. The upper portion 57 of the lock bolt is bent inwards toward the plate 15, and is provided with an oblique edge 58 (Fig. 4) corresponding to and coacting with the edge 83 of the plate 17. A boss 9 to the left (Fig. 1) is by means of screws 63 fastened to the bottom plate 2 which also has a corner boss 11 to the right. The boss 9 has a channel 62 acting as a guide for the bolt shank 56 which is covered by a plate 61 fixed to the same boss by means of screws 60. A lever 31 is by means of a bolt 30 swingably mounted on the right corner boss 11 and is provided with two abutments 32, 33 adapted to cooperate, respectively, with the abutment 79 and the portion 57 of the bolt.

The angular member 42 is formed with a central hub 43 which is screwed onto the end of the lock spindle 48. In the angular arm 42 (which in Fig. 2 is turned downwards) and the central hub 43 is a troughgoing slot 44 for a key 45 which is inserted into the slot and into a corresponding slot 51 in the spindle 48, the latter slot being of a greater length than the slot 44, to afford adjustment such as required for variation in the thickness of doors.

The angular arm 42 is on each side provided with a notch 46 somewhat narrower than the thickness of the arm, so that at each notch an extending edge 47 is formed which edges as well as the notches are divided into two portions by the slot 44.

The key 45 has T-form as seen in Fig. 5 with two extensions 49, one on each side which are bent into the notches 46 after the key is inserted, by which the key is held in position and prevented for sliding axially. At the inner end 50 of the same

breadth as the diameter of the spindle which extension enters the inner portion of the slot 51 in the spindle to guide the key. The key 45 can in this manner be given a breadth as great as the diameter of the central hub 43 as well as a great length and goes through the spindle 48, so that the key is resting on both sides of the spindle and no play can arise when the key is correctly inserted. To insure tightness in spite of imperfections in the manufacture of the parts, the key may be slightly bent so as to develop a degree of binding action tending to maintain the key and spindle in proper relative position.

The operation of the devices is as follows.

In the position of the members in Fig. 1 the tumblers 19 are adjusted according to the right combination and the angular arm 42 is disposed to engage the bolt 55 and withdraw the same into the lock. Upon further turning of the angular arm the edge 58 (Fig. 4) of the bent portion 57 of the bolt will be pressed against the oblique edge 83 of the plate 77 (Fig. 4), so that the cross bar 78 is forced downwards into the notches 21 of the tumblers permitting the inward movement of the lock bolt which would not be possible, if the plate 77 would be held in the upper position on account of any one of the notches of the tumblers not being placed correctly underneath the cross bar. At the downward movement of the cross bar 78 the abutment 79 will press against the abutment 32 turning the lever 31.

When the lock bolt is fully pushed into the lock, the members are in the position shown in Fig. 4. On account of the rectilinear guiding of the cross bar the width of the notches in the tumblers can be substantially the same as the thickness of the cross bar, so that even a minor error in the adjustment of the tumblers will prevent the downward movement of the cross bar into the notches. Every force from the cross bar directed sideways against the tumblers is eliminated.

When locking the lock, the bolt 55 is pushed outwardly and the bent portion 57 of the bolt will engage the abutment 33 and turn the lever 31, whereby the abutment 32 will push the cross bar 78 upwardly out of the notches 21 of the tumblers, so that these can be turned back to locked position in known manner.

The details of the arrangement may obviously be subjected to different modifications within the scope of the appended claims. The cross bar 78 can be spring actuated and thus held in the upper position in order to eliminate the effect of a possible play between the lever 31 and the lock bolt.

What I claim is:

1. In a combination lock a movable spindle extending through the door, an adjusting arm attached to the spindle, a pivot pin, tumblers ro-

tatably mounted on said pin to be adjusted by said arm into unlocking position and provided with notches in said position being underneath a movable cross bar of corresponding width coacting with the lock bolt, and a rectilinear guide for said cross bar extending radially of and held in position by said pivot pin.

2. In a combination lock a movable spindle extending through the door, an adjusting arm attached to the spindle, a pivot pin, tumblers rotatably mounted on said pin to be adjusted by said arm into unlocking position and provided with notches in said position being underneath a movable cross bar of corresponding width coacting with the lock bolt, a rectilinear guide for said cross bar held in position by said pin, and a thrust member for limiting movement of said cross bar.

3. In a combination lock a movable spindle extending through the door, an adjusting arm attached to the spindle, a pivot pin, tumblers rotatably mounted on said pin to be adjusted by said arm into unlocking position and provided with notches in said position being underneath a movable cross bar of corresponding width coacting with the lock bolt, extensions on said cross bar, and a rectilinear guide held in position by said pivot pin and engaging said extensions.

4. In a combination lock a movable spindle extending through the door, an adjusting arm attached to the spindle, tumblers rotatably mounted to be adjusted by said arm into unlocking position and provided with notches in said position being underneath a movable cross bar of corresponding width coacting with the lock bolt, the cross bar being guided by rectilinear guides when entering said notches, said cross bar being a separate member free from the lock bolt, the lock bolt actuating the cross bar into and out of the notches, the latter movement being obtained by means of an intermediate swingable lever.

5. In a combination lock a movable spindle extending through the door, an adjusting arm attached to the spindle, tumblers rotatably mounted to be adjusted by said arm into unlocking position and provided with notches in said position being underneath a movable cross bar of corresponding width coacting with the lock bolt, the cross bar being guided by rectilinear guides when entering said notches, said cross bar being a separate member free from the lock bolt, the lock bolt actuating the cross bar into and out of the notches, the latter movement being obtained by means of an intermediate swingable lever, said cross bar being spring actuated to be held in the uppermost position independable of said lever.

OLOF HAGE.
